of California

Filed Aug. 2, 1965, Ser. No. 86,379

Term of patent 14 years

(Cl. D62—3)

FIG. 1 is a side elevational view of a powered ventilator showing my new design;

FIG. 2 is a plan view;

FIG. 3 is an end elevational view; and

FIG. 4 is a perspective view thereof.

The side opposite that shown in FIG. 1 has the same appearance as FIG. 1. The end opposite that shown in FIG. 3 has the same appearance as FIG. 3.

I claim:

The ornamental design for a powered ventilator, substantially as shown and described.
